CLAIM

The ornamental design for a data access device, as shown and described.

DESCRIPTION

FIG. 1 is a perspective view of a data access device showing my new design;

FIG. 2 is a right side view thereof;

FIG. 3 is a top plan view thereof;

FIG. 4 is a front view thereof;

FIG. 5 is a bottom plan view thereof;

FIG. 6 is a left side view thereof;

FIG. 7 is a rear view thereof; and,

FIG. 8 is a perspective view showing the data access device in an operating condition.

The broken lines in FIG. 8 are included for the purpose of illustrating environmental structure only and form no part of the claimed design.
